UNITED STATES PATENT OFFICE

HIRAM ALLEN, OF WILLIAMSBURG, KANSAS

WIRE SPLICER

Application filed May 29, 1928. Serial No. 281,490.

This invention aims to provide novel means for twisting a piece of wire, one object of the invention being to provide a novel form of twister, and another object of the invention is 5 to provide novel means for rotating the twister.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Figure 1 is an elevation showing a device constructed in accordance with the invention;

Figure 2 is an elevation wherein the device is viewed at right angles to the showing of Figure 1;

Figure 3 is an elevation showing the opposite side from that which appears in Figure 2;

Figure 4 is an elevation like Figure 1 but showing the parts as they will appear when the final twists are given to the wire;

Figure 5 is a section on the line 5—5 of Figure 3;

Figure 6 is a section on the line 6—6 of Figure 3;

Figure 7 is an elevation showing a modification;

Figure 8 is a section on the line 8—8 of Figure 7;

Figure 9 is an elevation showing a modification;

Figure 10 is an elevation wherein the device depicted in Figure 9 is shown at right angles to that figure, parts being broken away;

Figure 11 is a section on the line 11—11 of Figure 10.

Referring to the form shown in Figures 1

to 6, there appears a head 1, made of metal, and provided at one end with a projection 4 located to one side of a central longitudinal passage 2 in the head 1. A slot 3 extends inwardly from the outer surface of the head 1 through the head and through the projection 4, the slot 3 communicating with the central longitudinal passage 2. In the side edges of the projection 4 there are notches 5 forming overhanging shoulders 6. The head 1 has transverse openings 7 and 8 located on opposite sides of the slot 3. The opening 7 is of a common diameter from end to end. The opening 8 at its inner end is of the same diameter as the opening 7, but the outer end 60 of the opening 8 is reduced in diameter as shown at 9, to form an internal shoulder 12 in the head 1. The means for rotating the head 1 is in the form of a bar or operating member 10 which is slidable in the openings 7—8—9, the bar 10 being of the same diameter as the part 9 of the opening. The bar 10 has projections at its ends. These projections 11 are small enough to move through the openings 7 and 8, but are too large to 75 move through the opening 9.

In practical operation, the bar or operating member 10 is slid endwise into the position shown in Figure 5, so that the bar does not extend across the slot 3, one of the projections 11 being received in the opening 8.

The wire, then, is inserted through the slot 3 into the central longitudinal passage 2. The bar 10 is slid across the slot 3, into the position shown in Figures 1 and 2, and, thus, 85 the wire is held in the passage 2. The wire, marked by the numeral 14, is formed into a loop 15. One end of the loop 15 is extended across the inner surface of the projection 4, as is shown at 16 in Figure 1, and the twisting operation is begun. As the wire is being twisted, it is received in one of the notches 5 and is retained in place against the end of the head 1 by the corresponding shoulder 6. After the wire has been twisted to a considerable extent, the free end of the wire is received in the slot 3 and is made to fit in one or the other of a pair of shallow seats 17 formed in the projection 4 on opposite sides of the slot 3. By continuing the twisting op-

eration with the free end of the wire in the slot 3, as shown in Figure 3, the wire may be twisted down close, at its end, in a way which will be understood readily when the operation of the device is considered in connection with Figures 3 and 4. The bar 10 exercises a double function, in that it acts as an operating member, and also as a latch to hold the shank of the wire in the passage 2.

10 In Figures 7 and 8, parts hereinbefore described have been designated by numerals previously used with the suffix "a".

13 The head 1^a is of polygonal form, as shown at 19, and has a flange 18 at one end. Because the head is of polygonal form, as shown at 19, it can be rotated by means of a wrench (not shown) instead of the bar 10 of Figure 1.

15 In Figures 9, 10, and 11, parts hereinbefore described, have been designed by numerals previously used, with the suffix "b".

20 The head 1^b has a reduced bearing 20 which is held against a ratchet wheel 21 by rivets 22, the ratchet wheel 21 having a reduced bearing 23. The numeral 24 marks a handle made up of plates 25 held together by securing element 26. The plates 25 are separated at one end to form the members 27 and 28 of a fork. The ratchet wheel 21 extends between the members 27 and 28 of the fork. The bearing 23 of the ratchet wheel 21 is journaled in the member 27 of the fork, and the bearing 20 of the head 1^b is journaled in the member 28 of the fork. The members 27 and 28 of the fork are provided with slots 29, and when the twister head 1^b is rotated into the proper position, the slot 3^b in the twister head will register with the slots 29 to admit the wire into the central longitudinal passage 2^b.

25 A pawl 30 is located between the parts 27 and 28 of the fork and is mounted on a pivot element 31 carried by the members 27 and 28. The pawl 30 is constrained by a spring 32 to engage the ratchet wheel 21, the spring being held at 34 (Figure 9) in the plates 25 of the handle, and being engaged around the pin 33 in the parts 27 and 28 of the fork.

30 The modification disclosed in Figures 9, 10 and 11 resides, essentially, in the means for rotating the twister head. It will be obvious that the handle 24 may be swung back and forth, the pawl imparting an intermittent rotary motion to the twister head.

What is claimed is:—

35 1. In a device of the class described, a head having a projection at one end and provided with a longitudinal passage, the head being provided with a longitudinal slot leading inwardly from the periphery of the head through the projection and to the passage, and an operating member slidable in the head, transversely thereof, to and from a position across the slot.

40 2. In a device of the class described, a head having a projection at one end and provided

45 with a longitudinal passage, the head being provided with a longitudinal slot leading inwardly from the periphery of the head to the passage, and an operating member slidable in the head transversely thereof, to and from a position across the slot. 70

50 3. In a device of the class described, a head having a projection at one end and provided with a longitudinal passage, the head being supplied with a longitudinal slot leading inwardly from the periphery of the head to the passage, the head being equipped with oppositely-disposed, transverse openings located on opposite sides of the slot, and a bar having right-line sliding movement in the openings, to and from a position across the slot, the bar being long enough so that it will serve as an effective operating handle for rotating the head. 75

55 4. In a device of the class described, a head having a projection at one end and provided with a longitudinal passage, the head being supplied with a longitudinal slot leading inwardly from the periphery of the head to the passage, the head being equipped with oppositely-disposed transverse openings located on opposite sides of the slot, and a bar having right-line sliding movement in the openings, to and from a position across the slot, the bar being long enough so that it will serve as an effective operating handle for rotating the head, the head having a shoulder located within one of the openings, the bar being provided with a projection which engages the shoulder to prevent the bar from being pulled entirely out of the head when the bar is retracted to open the slot. 80

60 5. In a device of the class described, a head having a projection on one end and provided with a longitudinal passage, the head being supplied with a longitudinal slot leading inwardly from the periphery of the head to the passage, the head being equipped with oppositely-disposed, transverse, large and small openings, the large opening being located on one side of the slot, and the small opening being located on the other side of the slot, and a bar having right-line sliding movement in the openings, to and from a position across the slot, the bar being long enough so that it will serve as an effective operating handle for rotating the head, the bar being provided with a projection of such size as to pass through the large opening and engage the head at the small opening, to prevent the bar from being pulled entirely out of the head, when the bar is retracted to open the slot, the bar fitting closely but slidably in the small opening. 100

65 In testimony that I claim the foregoing as my own, I have hereto affixed my signature. 105

HIRAM ALLEN.
